UNITED STATES PATENT OFFICE.

WILLIAM ROSS, OF CHICAGO, ILLINOIS.

GRIZZLY OR SCREEN FOR GRADING MATERIAL.

1,414,156.

Specification of Letters Patent. Patented Apr. 25, 1922.

Application filed May 6, 1921. Serial No. 467,474.

To all whom it may concern:

Be it known that I, WILLIAM Ross, a subject of the King of Great Britain, and a resident of Chicago, in the county of Cook 5 and State of Illinois, have invented a certain new and useful Grizzly or Screen for Grading Material, of which the following is a specification.

This invention relates to screens for grading material, and relates particularly to what are commonly known as grizzlies and screens, of the general type which forms the subjects-material of U. S. Letters Patent heretofore issued to me, to wit, No. 1,321,773, 15 dated Nov. 11, 1919, and No. 1,332,305, dated March 2nd, 1920.

Grizzlies or screens of the general type to which the invention relates, comprise two sets of bars supported substantially horizontally and which move in closed orbits of different lengths, the orbits of said bars coinciding in the screening zone, in which said bars will be separated by spaces of predetermined size, said orbits diverging as the 25 bars pass out of the screening zones, thus automatically increasing the distances between bars moving in different orbits, such spaces attaining maximum size when said bars are traversing the sections of their orbits directly beneath the screening zone, whereby "fines" which pass through the bars in the screening zone will pass freely through the spaces between said bars when traversing the lower or return portions of 35 their orbits.

For purposes of convenient reference and to distinguish the bars which form different series and move in different orbits, the bars which move in the shorter orbit will be referred to as "main" bars and the bars which move in the longer orbit will be designated "displaceable" bars.

In addition to retaining the advantages and improvements secured by my said prior 45 patents, the present invention has for its object to still further improve and perfect the construction and operation of grizzlies or screens of the general type specified.

Among specific objects of the present invention, the following may be enumerated:

1. To insure the release and discharge of pieces of material which may become lodged or wedged between the bars of the grizzly in the screening zone, as said bars pass out 55 of the screening zone.

2. To provide means for taking up wear

and resultant elongation of the chain belts which carry the screen bars with the teeth of the sprocket wheels to which said chain belts are adjusted.

3. To prevent oversize material from falling through the openings between the bars as they pass out of the screening zone, due to the enlargement of the spaces between said bars, as they pass around the sprocket 65 wheels to which the chain belts carrying the same are adjusted.

4. To prevent oversize material, particularly of a thin and slabby character, which may pass through the bars in the screening 70 zone from becoming trapped at the rear inner portion of the screen.

5. To prevent oversize, elongated, thin or slabby material from passing through the bars in the screening zone with the fines; and 75

6. To provide a construction whereby pieces of material which may become lodged or wedged under the lower edges of the top skirt plates—which protect the sides of the screen—will be automatically released in 80 the operation of the grizzly or screen.

To attain the foregoing and other objects of the invention, my improved grizzly or screen, comprises the various features, combinations of features and details of construction hereinafter described and claimed.

In the accompanying drawings, in which my invention is fully illustrated,

Figure 1 is a sectional side elevation of a grizzly embodying my invention, the section being taken substantially on the line 1—1 of Figure 2.

Figure 2 is a front view thereof, the grizzly proper being shown in central, vertical section.

Figure 3 is a fragmentary view, on an enlarged scale, of the grizzly proper shown in Fig. 1.

Figure 4 is a view from the right hand side of Fig. 3.

Figure 5 is a sectional side elevation illustrating screening means proper constructed and arranged for effecting certain objects of the invention.

Figure 6 is a sectional elevation on the 105 line 6—6 of Fig. 5.

Figure 7 is a top plan of screening means proper constructed and arranged for effecting certain objects of the invention; and

Figures 8 and 9 are fragmentary views 110 corresponding substantially to Figs. 5 and 6, respectively, illustrating a modification.

To effect the object of the invention, as it relates to providing a construction which will insure the release and discharge of material lodged or wedged between adjacent bars in the screening zone, as said bars reach a point at which their orbits begin to diverge, the construction of my improved grizzly or screen is as follows, particular reference being made to Figs. 1 to 4, inclusive, of the drawings:—

Rotatably mounted in suitable bearings on the side frames, is a shaft 2 secured to which are spaced sprocket wheels 3, adjusted to which are chain belts 4.

Secured in said sprocket wheels are main grizzly bars 5 and secured to the links of the chain belt are the displaceable bars 6. The pitch of said main and displaceable bars is the same and the displaceable bars 6 engage marginal notches 7 formed in said sprocket wheel, the displaceable bars alternating with the main bars and the relation being such that in the screening zone, the orbits of said main and displaceable bars 25 are substantially coincident.

To provide for displacement of the bars 6 relatively to the main bars 5 at the under or return sections of their orbits, the orbit of the displaceable bars 6 is longer than the orbit of the main bars 5, there being, as shown, one more displaceable bar than there are main bars and one more link in the chain belts 4 than there are notches 7 in the sprocket wheels 3. Thus, gravity 35 will cause the chain belts 4 and with them the displaceable bars 6 to sag and hang below the main bars 5 at the under sides of the sprocket wheels 3.

The links of the chain belts 4 are articulated end to end and the displaceable bars 6 connected to said chain belts by means of journals 8 formed at the ends of said displaceable bars which engage corresponding pivot holes formed in the overlapping ends of the links of said chain belts.

In accordance with my present improvements, the link of the chain belts are made in separate sections, the ends of said sections overlapping and being pivotally connected by pivot pins 9 fitted to suitable bearings formed in the overlapping ends of said link sections.

Where the chain belts 4 and the displaceable bars 6 are in full engagement with the sprocket wheels 3, the pivot pins 9 are supported in substantial radial alignment with and outside of and eccentric to the main bars 5. With this construction it is obvious that when divergence of the chain belts 4 from the sprocket wheels 3 begins, the displaceable bars 6 will move outwardly away from the sprocket wheels 3 so as to effect disengagement of said displaceable bars from the notches 7, on arcs of circles 95 which will diverge from arcs of correspond-

ing circles described from the axis of the main bars 5 corresponding to the pivot pins 9, respectively, thus providing corresponding clearance between the main and displaceable bars at said point of divergence. 70

In the preferable construction shown, the means for thus supporting the pivot pins 9 are as follows:—

Formed on the sprocket wheels 3 are flanges 10, threaded through which are 75 thrust screws 11 the ends of which bear against the inner edges of the intermediate link members of the chain belts 4 in line with the pivot pins 9, the ends of said screws being preferably rounded and said chain belt members being preferably provided with rounded ends of said screws.

As shown, the thrust screws 11 extend substantially radially of the sprocket wheels 4 and are adapted to be secured in different adjusted positions by means of lock nuts, in a familiar manner.

Said thrust screws 11 also provide convenient means for adjusting the operative lengths of the chain belts 4 to compensate 90 for any elongation of said chain belts which may be caused by wear in the pivot joints, whereby exact register of the displaceable bars 6 with the notches 7 in the sprocket wheels 3 may be maintained at all times, 95 effectively preventing "jumping" of said bars and disengagement thereof from said notches 7.

In Figs. 5 and 6 of the drawings, I have shown a modified construction in which both 100 the main and the displaceable bars are carried by sprocket chains and in which both the main and displaceable bars, instead of being connected to their respective chain belts at the pivot joints thereof, are secured 105 in lugs or projections formed on link members of said chain belts.

In said modification, the screening zone of the grizzly is formed by the upper laps or sections of the chain belts, the orbits of 110 which coincide.

With the main and displaceable bars supported in the manner shown, it is obvious that when the chain belts pass around the sprocket wheels which define opposite ends 115 of their orbits, respectively, the flexure of said chain belts will increase the distance between adjacent bars, which would permit oversize material to fall between said bars in the screening zone, which would become 120 mixed with the fines, thus impairing the uniformity of the screened material.

In accordance with my present invention I contemplate remedying this objectionable feature by mounting a drum upon the shaft 125 which carries the sprocket wheels at the discharge end of the screen which may be plain, but which, preferably, will be provided with longitudinal ribs which will form a series of pockets in the surface there- 130

of adapted to receive any material which may fall between the screen bars and which will later be discharged upon the tail board for the oversize material when the pockets 5 of said drum containing such oversized material are inverted as they approach and pass the under side of the drum.

In Figs. 5 and 6 I have also shown a construction for effecting the object of the invention as it relates to preventing oversize material, particularly material of a slabby character from being trapped at the rear end of the lower or return sections of the screen.

15 In accordance with my present invention, I attain the foregoing object by positioning the rear sprocket wheels for the chain belts which carry the displaceable bars, in the rear of the corresponding sprocket wheels 20 for the chain belts which carry the main bars, thereby maintaining spaces of maximum width between the main and displaceable bars until said bars are again brought into position in which their orbits coincide.

25 Referring now to Figs. 5 and 6 the numerals 12, 13, 14 and 15 designate sprocket wheel shafts rotatably mounted in suitable bearings on the machine frame, 16, 17, 18 and 19 pairs of sprocket wheels secured to 30 said shafts in spaced relation, 20 and 21 chain belts adjusted to said sprocket wheels, 22 main bars carried by the chain belt 20, and 23 displaceable bars carried by the chain belts 21, said bars being secured in lugs 24 35 formed on link members of said chain belts 20 and 21 and which project outwardly therefrom.

With the described construction it is obvious that as the bars 22 and 23 pass around 40 the sprocket wheels 16 secured to the shafts 12, the flexure of the chain belts will operate to automatically increase the distance between said bars thereby permitting oversize material to fall between the same. To 45 prevent this, a drum 25 is secured to the sprocket shaft 12, the surface of which extends into close proximity to the screen bars as they pass around the sprocket wheels secured to said shaft 12, thus closing the spaces 50 between said bars.

Said drum may be made plain but will preferably be provided with longitudinal ribs forming pockets 26 in the surface of said drum, the ribs forming said pockets 55 being spaced apart distances substantially equal to the distance between the screen bars as they pass around the sprocket wheels 12, and being so positioned that their rear sides will extend substantially tangent to the 60 rear sides of the screen bars as they pass around said drum.

With the described construction, as said pockets come into inverted position, the contents thereof will be discharged on to the 65 tail board of the screen, thereby effectually

preventing oversize material from being carried rearwardly with said screen bars as they pass out of engagement with the sprocket wheels 16, and again becoming mixed with the fines which have passed 70 through the screen section of the grizzly.

With the construction shown in said Figs. 5 and 6, I am also able to effect the object of the invention as it relates to preventing oversize material from being trapped at the 75 return ends of the lower sections of the screen, this end being attained by locating the sprocket wheels 18 for the chain belt 21 which carry the displaceable bars 23 at a distance beyond the sprocket wheels 17 80 for the chain belts 20 which carry the main bars 22, thus maintaining spaces of maximum size between the main and displaceable bars 20 and 21 until said bars again pass into the screening zone.

As the invention relates to preventing oversize, elongated, thin or slabby material from passing through the screen with the fines, I attain the object of the invention by dividing the spaces between adjacent bars 90 into sections, the dimension of which transversely of the screen is substantially equal to the distance between adjacent screen bars. This may be done in a simple manner by securing pins 27 in the main and displaceable bars, the pins secured in different bars being preferably arranged alternately, and said pins being of such length that they will extend into close proximity to adjacent bars, all as clearly shown in Fig. 4 of the drawings.

To be effective, it is necessary that the pins 27 shall be located substantially in the surface defined by the orbits of the main and displaceable bars and to this end, said 105 bars are pinned or otherwise secured in position to support said pins in the desired relation.

As modified means for maintaining spaces of maximum size between the main and displaceable bars at the return ends of the lower section of the screen, thereby preventing oversize material, which may pass through the bars in the screening zone with the fines, from becoming trapped at the return end of the lower section of the screen—instead of sprocket wheels secured to different shafts mounted in spaced relation, as shown in Figs. 5 and 6—I contemplate the use of sprocket wheels of different sizes for 110 supporting the chain belts which carry the main and displaceable bars, respectively, at their return ends, said sprocket wheels being rotatably mounted, respectively, on offset sections of a non-rotatable shaft.

This modification is shown in Figs. 8 and 9 of the drawings, in which 28 designates the chain belt which carries the main bars, 29 the chain belt which carries the displaceable bars, 30 and 31 off-set sections of 130

4
a shaft secured against rotation upon the machine frame, 32 relative small sprocket wheels to which the chain belt 27 is adjusted, and 33 relatively large sprocket wheels to which the chain belts 29 are adjusted, said sprocket wheels 32 being mounted on the sections 30 of the supporting shaft and the sprocket wheels 33 on the shaft sections 31, and the relation being such that the orbits 10 of the screen bars will coincide in the screening zone.

In accordance with my present invention, also, I attain the object of the invention as it relates to providing a construction where 15 by pieces of material which become lodged under the lower edges of the top skirt plates will be automatically released in the operation of the grizzly, by making said top skirt plates of such shape that their lower edges will diverge towards the discharge end of the screen, as shown at 34, Fig. 7, whereby movement of said screen in operation will operate to dislodge pieces of material which have worked under the edges 25 of said top skirt plates, in an obvious manner.

I claim,

1. In a grizzly of the type specified, the combination of main and displaceable bars 30 arranged and which move in closed orbits, the orbit of said displaceable bars being longer than the orbit of said main bars, said orbits coinciding in the screening zone, and means for movably supporting said displaceable bars whereby displacement thereof will be on lines divergent to circles described from the centers of adjacent rear main bars, substantially as described.

2. In a grizzly of the type specified, the combination of main and displaceable bars 40 arranged and which move in closed orbits, the orbit of said displaceable bars being longer than the orbit of said main bars, said orbits coinciding in the screening zone, and 45 means for movably supporting said displaceable bars so constructed and arranged that displacement of said bars will be from centers eccentric to and outside of said main bars, substantially as described.

50 3. In a grizzly of the type specified, the combination of main and displaceable bars, chain belts which carry said displaceable bars, sprocket wheels to which said chain belts are adjusted, said displaceable bars being connected to alternate joints of said chain belts and means for supporting the joints of said chain belts intermediate said displaceable bars eccentrically to and outside of the axes of the main bars, substantially as 55 described.

4. In a grizzly of the type specified, the combination of main and displaceable bars, chain belts which carry said displaceable bars, sprocket wheels to which said chain 60 belts are adjusted, and means for adjusting

the operative lengths of said chain belts to compensate for wear in the joints thereof, substantially as described.

5. In a grizzly of the type specified, the combination of main and displaceable bars, 70 chain belts which carry said displaceable bars, sprocket wheels to which said chain belts are adjusted and means for adjusting the operative lengths of said chain belts to compensate for wear in the joints thereof, 75 said means comprising flanges formed on said sprocket wheels and thrust screws threaded through said flanges, the outer ends of which engage link members of said chain belts substantially in line with the joints 80 thereof intermediate said displaceable bars, substantially as described.

6. A grizzly substantially as specified in claim 3, in which the joints of the chain belts intermediate the displaceable bars are supported by thrust screws threaded through flanges formed on the sprocket wheels to which said chain belts are adjusted, the ends of which bear against members of the sprocket chain substantially in line with said 90 intermediate chain joints, substantially as described.

7. In a grizzly of the type specified, the combination of main and displaceable bars, chain belts which carry said displaceable 95 bars, sprocket wheels to which said chain belts are adjusted, pins secured in said bars and which project into the spaces between adjacent bars and means to secure bars carrying said pins from turning, substantially 100 as described.

8. In a grizzly of the type specified, the combination of main and displaceable bars, chain belts which carry said displaceable bars, sprocket wheels to which said chain 105 belts are adjusted, pins secured in said bars and projecting into the spaces between adjacent bars, respectively, and means to secure bars carrying said pins from turning, substantially as described.

9. In a grizzly of the type specified, the combination of main and displaceable bars arranged and which move in closed orbits, the orbit of said displaceable bars being longer than the orbit of said main bars, said 110 orbits coinciding in the screening zone, the means for supporting said main and displaceable bars comprising chain belts to which said main and displaceable bars are secured, respectively, sprocket wheels to 115 which said chain belts are adjusted, the sprocket wheels which support the chain belts for said main and displaceable bars, respectively, at their return ends being mounted eccentrically to each other, the relation being such that spaces of substantially maximum size will be maintained between said main and displaceable bars at the return ends of the lower sections of their orbits, 120 substantially as described.

10. A grizzly of the type specified in claim 9, in which the sprocket wheels for the return ends of the chain belts which carry the displaceable bars, are mounted beyond the 5 orbits of the main bars, substantially as described.
11. In a grizzly of the type specified, the combination of main and displaceable bars arranged and which move in closed orbits, 10 the orbit of said displaceable bars being longer than the orbit of said main bars, said orbits coinciding in the screening zone, and means to prevent oversize material from passing through the spaces between the grizzly bars at the discharge end of the grizzly and becoming intermixed with the fines, substantially as described.
12. A grizzly substantially as specified in claim 11, in which a drum is mounted on the 20 sprocket wheel shaft at the discharge end of the grizzly, the surface of which extends into close proximity to the grizzly bars passing around said sprocket wheels, substantially as described.
- 25 13. A grizzly as specified in claim 12, in which the drum is provided with longitudinal ribs forming series of pockets in the surface of said drum, the relation being such that the grizzly bars passing around said drum will be in substantial alignment with 30 the ribs thereon, substantially as described.
14. A grizzly substantially as specified in claim 13, in which the rear sides of said ribs will extend substantially tangent to the rear sides of the grizzly bars passing around said 35 drum, substantially as described.
15. In a grizzly of the type specified, the combination of main and displaceable bars arranged and which move in closed orbits, the orbit of said displaceable bars being 40 longer than the orbit of said main bars, said orbits coinciding in the screening zone, and top skirt plates, the lower edges of which diverge towards the discharge end of the grizzly, substantially as described.

In witness that I claim the foregoing as my invention, I affix my signature this 3rd day of May, A. D. 1921.

WILLIAM ROSS..
